GARMENT OR IRONING PRESS

Ernest Davis, Syracuse, N. Y., assignor to The Prosperity Company Inc., Syracuse, N. Y., a corporation of New York

Application August 14, 1929, Serial No. 385,794
Renewed August 10, 1933

13 Claims. (Cl. 68—9)

This invention relates to pressing machines, as garment, laundry or ironing presses which are power actuated and provides a control mechanism by which any degree of final pressure may be obtained or varying degrees of final pressure may be obtained during the pressing operation as desired. For particular types of work, accurate control of the final pressure is desirable.

The invention has for its object a particularly simple, efficient and sensitive control by which graduated pressure or any degree of final pressure can be applied between the pressing elements, or jaws of the machine by the motor means and also a control by which the machine can be locked under any predetermined amount of pressure and if desired, the pressure diminished any degree without opening the press.

The invention consists in the novel features and in the combinations and constructions hereinafter set forth and claimed.

In describing this invention, reference is had to the accompanying drawings in which like characters designate corresponding parts in all the views.

Figure 1 is a side elevation of a pressing machine embodying this invention.

Figure 2 is a diagrammatic view illustrating the motor, the control means therefor and the locking means, the latter two means being in section.

Figure 3 is a diagrammatic view similar to Figure 2 illustrating another form of locking means.

Figure 3a is a detailed fragmentary view showing a portion of the operating mechanism of Figure 3 with parts broken away to show the connection between the links.

Figure 4 is a plan view of the treadle and lock lever shown in Figure 3.

Figure 5 is a view similar to Figure 2 of another form of control and locking means with most of the parts being shown in section.

Figures 6 and 7 are views similar to Figure 2 of two additional forms of locking means, these views also showing the essential parts in section.

The invention is applied to a conventional form of garment and laundry or ironing press, which is actuated by a fluid pressure operated motor means.

The cooperating pressing elements or jaws of the machine or press here illustrated, are a buck 1 and a head 2 movable toward and from the buck. The buck is mounted on a suitable bracket or bolster 3, which in turn is mounted on a suitable supporting frame 4, the head 2 being carried by

the usual frame or yoke lever 5 which is pivoted at 6 to an upright 7 rising from the frame.

The operating mechanism by which the press is opened and closed includes motor means having a cylinder 8 in which is a piston 9 connected through suitable motion transmitting mechanism to the head 2.

The motion transmitting mechanism may be of any suitable form, size or construction, and that here shown in addition to the lever 5 includes toggle links 10 and 11 pivoted together at 13, and respectively at 14 and 15 to the rear arm of the yoke lever 5 and to the base of the frame 4. The toggle link 11 has a forwardly extending arm 16 which is pivoted at 17 to the rod 18 of the piston 9. The piston is single acting and the press is opened, when the pressure in the cylinder 8 is released, by countersprings 19 and 20.

The means for supplying fluid pressure to the motor means and for regulating the pressure in the motor means comprises valve mechanism generally designated by the numeral 21. It comprises generally a casing having a pressure chamber 22 therein, an intake port 23 opening into the chamber 22, an outlet port 24 leading from the chamber, a spring pressed, normally closed intake valve 25 controlling the intake port 23, a spring pressed, normally open outlet valve 26 controlling the outlet port 24 and operated in guides slotted to permit the passage of air, a diaphragm 27 forming one side of the pressure chamber 22, a lever 28 fulcrumed between its ends at 29 on the diaphragm and coacting at one end with the stem 30 and at its opposite end with stem 31 of the intake and outlet valves 25 and 26 respectively, and an operating member 32 which compresses a spring 33 which acts on the diaphragm 27 with a pressure equal to the amount of pressure or compression applied to the spring 33 by the operator through the member 32.

The member 32 is a lever pivoted at 34 and having an arm 35 in the form of a cap which presses against the stem 36 of an abutment 37 thrusting against one end of the spring 33. The spring 33 is interposed between this abutment 37 and an abutment 38 which is carried by or presses against the central part of the diaphragm 27. The diaphragm 27 is held at its margins at 39 within the casing 21. A suitable returning spring 40 acts on the arm 35 of the operating member 32.

The operating member 32 is actuated by a single operator actuated control device, member, or foot plate 41, this being shown as pivoted at 42 to a fixed point, as a bracket 43, on the frame and as pivoted to the operating member 32 by a pin-

95

105

110

- and-slot connection at 44. The intake port 23 is connected to a feed pipe 45, which pipe is connected to any suitable source of supply of fluid under pressure as compressed air. The chamber 22 of the valve 21 is connected by a pipe 46 to a coupling 47 communicating with a port 48 in the head of the cylinder 8.
- By depressing the single control member or foot plate 41, the lever 32 will be actuated and compress the spring 33 an amount dependent upon the amount of foot pressure applied to the pedal 41, and the pressure of the spring 33 will be applied to the diaphragm 27 thus depressing the lever 28 and closing the exhaust valve 31 and opening the intake valve 30, the spring of the intake valve being preferably slightly heavier than the spring for the exhaust valve so that the exhaust valve closes before the intake valve opens. Thereupon air will flow from the feed line 45 into the chamber 22 and through the pipe 46 to the cylinder 8 to actuate the piston 9 therein and through the motion transmitting connections close the press under a pressure depending upon the amount of pressure applied by the operator 25 to the foot plate 41 and hence to the spring 33. The pressure builds up in the chamber 22 against the diaphragm 27 until it equalizes or slightly overcomes the pressure of the spring 33.
- To apply more pressure, the operator 30 presses the foot plate 41 further, thus additionally tensioning the spring 33 so that more pressure can build up in the chamber 22 and hence more pressure be applied to the piston 9 and the press head 2, until the pressure builds up in the chamber 22 to balance the pressure of the spring 33. It is obvious that any degree of pressure between the minimum and the maximum can be applied to the piston 9, and hence to the press head, depending upon the amount the spring 33 is tensioned by the pressure applied by the operator to the foot plate 41.
- The press described herein may also be operated in the following manner if desired. The foot plate 41 may be depressed to its full extent 45 whereupon the motor is actuated with full air pressure. Thereafter the foot pedal 41 may be released to an intermediate or midstroke position whereupon the compression of the spring 33 decreases so that the air pressure on the diaphragm 27 is greater than the opposing pressure exerted by the spring 33 and the exhaust valve 26 opens to exhaust some of the air from the motor cylinder 8 until the air pressure upon the diaphragm 27 is again balanced by the spring 33. 50 When this balance is obtained, the exhaust valve 26 closes and the press remains closed under decreased pressure between the jaws because of the decreased air pressure within the motor cylinder 8.
- It will be noted therefore that the intake valve 25 provides means to supply working fluid to the motor means. The outlet or exhaust valve 26 with the diaphragm 27, and spring 33 provide pressure regulating means, through which working fluid above a degree of pressure determined by the compression of the spring 33 may exhaust from the motor means. The pressure regulating means is connected to the motor means through the chamber 22 and the pipe 46. The control 55 means for the press or motor means comprises the foot pedal 41, lever 32, cap 35, abutment 36, spring 33, member 29, and lever 28 which is operable to actuate the working fluid supply means or intake valve 25, and renders the pressure regulating means inoperative to open its exhaust valve 26. The control means is then operable by releasing the pedal 41 to a midstroke or intermediate position to cut off the supply of working fluid by closing the valve 25 and renders the pressure regulating means operative to exhaust fluid from the motor means 8 because the compression of the spring 33 has been reduced thereby and the air pressure upon the diaphragm 27 overbalances the spring compression so that the spring pressed exhaust valve 26 opens to permit air to exhaust from the motor means. The air continues to exhaust until the air pressure against the diaphragm 27 no longer overbalances the compression of the spring 33 whereupon the spring 33 closes the exhaust valve 26 by overcoming its smaller spring. The exhaust valve 26 functions then as a check valve or check valve means through which working fluid escapes or exhausts above a determined degree of pressure. Since, in the form of invention shown in Figure 3, the compression of the spring 33^a is predetermined for each notch in the rack 63, the selection of any rack tooth for engagement by the pawl 61 by the operator sets the pressure regulating means in position to exhaust the fluid pressure 90 from the motor means at this predetermined pressure.
- In the form shown in Figures 1 and 2, the press is locked under any amount of pressure by closing the exhaust port 24 by means of a manually operated valve, so that, when the pressure builds up in the chamber 22 of the valve 21 sufficiently to balance or slightly overbalance the spring 33 and thus permit the exhaust valve 31 to open, the air is prevented from exhausting through the port 24 by the manually operated valve. 105
- A normally open locking valve 49 is contained in a casing 50 which is connected by a pipe 51 to the port 24. This valve is operated by a manual or lever 52 pivoted at 53 to the valve casing or the housing therefor and having an angular arm 54 pressing against the stem 55 of the valve 49. Obviously, movement of this lever upwardly in Figure 2 or laterally in Figure 1 will close the normally open valve 49. The valve 49 is locked 115 in its operated position by suitable means, as a diaphragm chamber 56 having a diaphragm 57 therein, which acts on a sliding stem 58 thrusting against an angular arm 59 on the lever 52. The pressure side of the diaphragm chamber 56 is connected by a duct 60 to the interior of the valve casing 50. Obviously, when the lever 52 is operated to close the valve 49, the air pressure will pass through the duct 60 to the diaphragm chamber 56 to actuate the diaphragm 57 therein and hold the lever 52 and the valve 49 in its operated position. 125
- To open the press the operator actuates the lever 52 downwardly in Figure 2 or laterally in Figure 1 to cause the arm 54 thereof to separate from the stem 55 of the valve 49 and as soon as the arm 54 of the lever 52 ceases to exert holding pressure on the stem 55, the valve 49 will open under the air pressure against it, and permit the air to exhaust through the pipe 51 from the chamber 22 and hence permit the air to exhaust from the cylinder back through the pipe 46 and chamber 22 out through the open exhaust valve 26, pipe 51, and valve casing 50. 130
- Obviously, the press head can be locked under any degree of pressure between minimum and maximum depending upon or determined by the amount the spring 33 is tensioned by the operator and can be locked under any degree of pressure by closing the valve 49 by means of the handle 140
- 150

52 and thereby preventing the escape of air from the chamber 22 after the operator removes his foot from the foot plate 41.

In Figures 3 and 4, the press is locked under any degree of pressure by locking the operating member 32^a mechanically in any one of its operated positions and thereby locking the spring 33^a of the valve 21^a under different degrees of pressure depending upon or determined by the force applied by the operator to the foot plate 41^a.

This mechanical locking means comprises a pawl 61 pivoted on the axis 44^a of the foot plate 41^a and having its tooth 62 coacting with a stationary rack 63. The pawl 61 is in the form of an angle lever having one arm 64 pivoted at 65 to the arm 66 of a lever 67 pivoted at 68 to a depending lug on the foot plate, the lever 67 having a head 69.

The lever 67 and parts operated thereby are located at one side of the foot plate with the head 69 located so as to be conveniently depressed by the foot. The lever 67 and the parts operated thereby are carried by the foot plate 41^a, and the arms 64 and 66 of the pawl 61 and lever 67 respectively form a toggle to lock the pawl 61 in determined position in the rack 63 so that the spring 33^a is locked in its operated position and hence the press is locked closed under a predetermined pressure. The operator after depressing the foot plate 41^a actuates the lever 67 by stepping on the head 69 thereof. The movement of the lever 67 through the toggle arms 64 and 66 moves the pawl 61 into engagement with one of the teeth of the rack 63, the toggle arms 64 and 66 moving upwardly. The joint 65 of the toggle is a pin-and-slot to permit such folding of the toggle. The pawl 61 is held in engagement with the rack 63 by a spring 70 encircling a rod 71 slidably and pivotally mounted at its ends at 72 and 73 to the toggle arms 64 and 66. The points 72, and 73 are shoulders and the spring 70 is compressed between the shoulders. When the toggle is folded upwardly, the spring 70 thrusts in opposite directions against the pawl 61 and lever 67 and hence holds them in their operated positions.

If the operator wishes to apply further pressure he further depresses the foot plate 41^a, and, as the pawl 61, during this operation ratchets over a tooth of the rack 63, the pawl 61 and its arm 64 is returned by this movement to a position which moves the lever 67 to throw the toggle back to its initial position, so that the operator must again make a conscious effort to lock the press closed; that is, he must operate the lever 67 by stepping on the head 69. Similarly the pressure between the pressing jaws may be decreased by releasing the ratchet locking means and permitting the pedal 41^a to rise and reengage the ratchet locking means in a tooth higher up on the rack 63.

To open the press, the operator merely steps on the foot plate 41^a and thus returns the pawl 61 to its out position by the ratcheting action of the teeth of the rack 63 on the pawl 61, and then removes his foot from the foot plate so that the spring 33^a is free to react to its initial position, and hence permit the intake valve 30^a of the valve 21^a to close and the exhaust valve 31^a to open.

Normally, the toggle arms 64 and 66 are in a straight line, so that the spring 70 acts in a straight line when the toggle arms are in dead center position.

In Figure 5, the exhaust valve 49^b is automatically closed when the press is closed instead of

being manually closed as by the lever 52, Figure 2.

In Figure 5, the outlet port 24^b of the regulating reducing and pop-off valve 21^b is connected by a pipe 51^b to the valve casing 50^b of the locking valve 49^b and the valve 49^b is operated by a diaphragm chamber 56^b having a diaphragm 57^b therein acting on a sliding stem 54^b which acts on a lever 52^b thrusting against the stem 55^b of the locking valve 49^b. The pressure side of the diaphragm chamber 56^b is connected by a pipe 75 to a pipe 76 communicating with a casing 77 on the side of the cylinder 8^b, the casing having a port 78 opening into the cylinder and arranged to be uncovered when the piston approaches the end of its power stroke. Obviously, when the port 78 is uncovered by the piston, the air pressure will pass back from the cylinder 8^b through the pipes 76, 75 to the diaphragm chamber 56^b and operate the diaphragm 57^b and move the same and hence lock the valve 49^b closed. Also, obviously, depression of the foot plate 41^b different distances, will cause different degrees of air pressure to flow from the chamber 22^b of the valve 21^b through the pipe 46^b to the cylinder and hence apply different degrees of pressure to the press head.

The press is opened by exhausting the air from the diaphragm chamber 56^b, and hence permitting the valve 49^b to open. This operation is effected by opening a normally closed, spring pressed, release valve 79 in a valve casing 80 which is connected by a pipe 81 to the pressure side of the diaphragm chamber 56^b, the valve 79 being operated by a means as a lever 82.

In Figure 6, the depression of the foot plate or treadle 41^c actuates the operating member 32^c to tension the spring 33^c different amounts and the air pressure from the chamber 22^c of the valve 21^c flows through the pipe 83 to diaphragm chamber 84 having a check valve 85 therein. This valve is carried by a diaphragm 86 in a chamber 84. The chamber 84 is connected at one side of the diaphragm 86 by a pipe 87 to the intake port 48^c of the cylinder 8^c.

The press is locked under different degrees of pressure by a normally closed, spring pressed intake valve 88 in a casing 89, the intake end of which is connected by a pipe 90 to the pipe 87. A normally open exhaust valve 91 is also located in the casing 89 and connected to the intake valve 88 by a stem 92, so that the two valves act as a unit. The casing 89 is connected between the valves by pipes 93, 94 to the diaphragm chamber 84 on the other side of the diaphragm 86. Preferably, there is an additional diaphragm 95 located in the chamber 84, these being arranged one above the other and the space between them being open to the outer air through ventilator openings 96. The diaphragms are provided with metal buttons on heads 97 and 98 respectively located centrally of the diaphragms. The heads thrust against each other.

The valves 88 and 91 are operated by means of a manual or lever 99 which through an intermediate lever 100 acts upon the stem 101 of the exhaust valve 91. After the foot plate 41^c is depressed, the press may be locked in closed position by depressing the lever 99 permitting the air to enter from the pipe 87 into the pipe 90, valve casing 89, pipes 93 and 94 to the diaphragm chamber 84 against the diaphragm 95, thus holding the check valve 85 closed so that the press is held under any predetermined degree of pressure, the valves 88 and 91 are locked in their operated positions by the action of a diaphragm 130

102 located in a diaphragm chamber 103, the pressure side of which is connected to the interior of the valve casing 89 by a duct 104.

5 The diaphragm 102 acts upon a sliding stem 105 which thrusts against the intermediate lever 100.

10 The operator first depresses the pedal or foot plate 41^c a predetermined amount depending upon the amount of pressure desired, so that, air passes 10 from the feed line 45^c to the pressure chamber 22^c, thence through the pipe 83, past the check valve 85 in the diaphragm chamber 84, thence through the pipe 87 to the cylinder 8^c to actuate the piston therein and close the press under a 15 degree of pressure depending upon the distance the foot plate 41^c is depressed.

15 The operator then depresses the locking lever 99 to open the intake valve 88 and close the exhaust valve 91, so that air can pass from the 20 pipe 87 through the pipe 90, valve casing 89, pipes 93, 94 to the diaphragm chamber 84 above the diaphragm 95 and hold closed the check valve 85 and lock the press under a predetermined degree of pressure.

25 To open the press, the air is exhausted from the diaphragm chambers 103 and 84 above the diaphragm 95 by opening a normally closed, spring pressed release valve 79^c located in a casing 80^c which is connected by a pipe 81^c to the 30 pipes 93 and 94. The valve 79^c is operated by a suitable trip lever 82^c.

35 In Figure 7, provision is made for closing the head first under zero pressure, that is, so that the press head is in light contact with the work 40 on the buck. The chamber 22^c of the valve 21^d is connected by the pipe 46^d to the cylinder 8^d, and the pipe 46^d on the cylinder is connected by a pipe 106 to a valve casing 107 having a normally closed, spring pressed relief valve 108 therein, the 45 casing 107 having an outlet 109 to the outer air. The operating member 32^d of the valve 21^d is connected by a link 110 to the foot plate or treadle 41^d and this link has a spring 111 thereon located between two spring abutments 112 and 113, the spring abutment 112 being normally spaced apart from a stop or shoulder 114 provided on the frame.

50 Initial depression of the foot plate or treadle 41^d brings the abutment 112 against the stop 114 and compresses the spring 33^d of the valve 21^d sufficiently to permit only enough air pressure to pass through the pipe 46^d to the cylinder to bring the press head of the machine down lightly on the work.

55 The purpose of the spring 111 is to enable the operator to feel a sudden increase in resistance after he has operated the treadle sufficiently far to supply working fluid to close the press under light pressure. When the abutment 112 strikes against the stop 114, further movement of the treadle member 41^d will cause the spring 111 to compress and will thus cause a sudden increase in the effort necessary to move the treadle member 41^d. If the operator moves the 60 treadle 41^d against this additional resistance the spring 33^d, of the valve, will be compressed sufficiently far to cause the valve to supply higher pressure than desirable for closing the press under light pressure. However the relief valve 108 will permit the excess pressure to escape. The 65 spring 33^d is of no value when operating the valve to close the press under light pressure. The spring 33^d is important in regulating the degree of heavy pressure applied by the pressing machine.

Further depression of the foot plate or treadle 41^d permits more air to enter the chamber 22^d and thence through the pipes 46^d and 106 will open the check valve 108 and permit the air to exhaust through the valve casing 107.

80 To obtain pressure greater than zero pressure, the operator must lock the relief valve 108 closed. This locking action is effected by a diaphragm 110^x in a diaphragm chamber 111^x, the diaphragm acting upon a sliding stem 112^x which acts through a rocker arm 113^x upon the stem 114 of the check valve to lock it closed. The area of the diaphragm 110^x is so great as compared with that of the valve 108 that when air at low pressure is admitted to the diaphragm chamber 111^x, the diaphragm 110^x will hold the valve 108 closed against the highest operating pressures which are used in the pipes 46^d and 106. The pressure side of the diaphragm chamber 111^x is connected by pipes 115 and 116 to the outlet port 24^d of the valve 21^d and this pipe 116 is closed in order to lock the valve 21^d in its 85 operated position by means, quite similar to that shown in Figure 2, consisting of a locking valve 49^d, in a casing 50^d, the valve being closed by a handle 52^d which acts through lever arms 54^d and 59^d respectively upon the stem of the valve 49^d and on a sliding stem 58^d, the latter coating with the diaphragm 57^d in a diaphragm chamber 56^d. The pressure side of the diaphragm 105 chamber is connected by a duct 60^d to the interior of the casing 50^d. Thus to apply pressure heavier than zero pressure, the operator must lock the check valve 108 closed by operating the lever 52^d before he can apply different degrees 90 of heavy pressure.

95 In operation, the operator depresses the treadle 41^d until the abutment 112 hits the stop 114, thus compressing the spring 33^d a predetermined amount and thereby opening the intake valve in the valve casing 22^d and closing the exhaust valve which controls the flow of fluid through the outlet port 24^d. Working fluid will then flow from the supply line 45^d through the intake valve, through the valve casing 22^d 100 and the conduit 46^d to the cylinder 8^d until the pressure in the valve casing 22^d balances the pressure of the spring 33^d and closes the intake valve. At this point the press will be closed under light pressure. If the operator should depress the treadle too far, the air which would tend to close the press under more than the predetermined light pressure will escape through the pop-off or safety valve 108. If the operator should release the treadle after the press has 105 been closed under light pressure, the air from the cylinder 8^d will escape through conduit 46^d, valve casing 22^d, the exhaust valve in the port 24^d, conduit 116, and exhaust valve 49^d.

110 If the exhaust valve 49^d is closed at the same time that the treadle is released, the press will be locked under light pressure.

115 In order to obtain heavy pressure after the press has been closed under light pressure, the exhaust valve 49^d is closed and the treadle released. Working fluid will then flow from the cylinder 8^d to the conduit 116 as described above and since the exhaust valve 49^d is closed motive fluid will flow through the conduit 115 to operate the diaphragm 110^x to lock the pop-off or safety valve 108 against opening. By then again depressing the treadle 41^d, any desired degree of 120 heavy pressure may be obtained.

125 In order to release heavy pressure the exhaust valve 79^d is opened and the treadle held in its 130 light pressure position.

The press is opened completely as in Figure 5 by a trip lever 82^a for opening a normally closed, spring pressed, release valve 79^a in a valve casing 80^a, which casing is connected by a pipe 81^a to the pressure side of the diaphragm chamber 56^a and by completely releasing the treadle 41^a.

In any form of my invention, obviously, graduated pressure can be applied by merely depressing the foot plate different distances and thereby tensioning or compressing the controlling 10 spring of a valve different distances.

What I claim is:

1. In a garment or laundry pressing machine, comprising in combination, cooperative pressing elements, one of which is movable toward and from the other; operating mechanism for the movable pressing element including a fluid operated motor; control means for the motor including valve means having a spring pressed movable element; operator actuated means cooperating with said spring and operable into different positions to regulate the tension of said spring and apply different degrees of pressure to said movable element of the valve means which regulates the supply of fluid to the motor; and means for locking said operator actuated means in any one of its operated positions. 15
2. In a pressing machine, cooperating pressing elements, one of which is movable toward and from the other, motor means for actuating the movable element, control means for the motor means, an operator-operated member for controlling the operation of the control means, said control means including an element movable different distances by the operator-operated member to vary the actuation of the motor and the movable pressing element to deliver different degrees of pressure, and means for locking the operator-operated member in any one of a plurality of operated positions. 30
3. In a pressing machine, cooperating pressing elements, one of which is movable toward and from the other, fluid pressure operated motor means for actuating the movable element, means for controlling the flow of motive fluid to the motor including a casing having a pressure chamber, inlet and outlet valves to said chamber, springs normally holding the inlet valve closed and the outlet valve open, an operator-operated member and resilient means operated thereby for operating the valves against their springs with a force dependent upon the force applied by the operator to the operator-operated member, means connecting the chamber to the motor, and an operator-operated valve for preventing exhaust past the outlet valve of said chamber and thereby locking any predetermined amount of pressure in said chamber and hence locking the press closed under any predetermined amount of pressure. 45
4. In a pressing machine, cooperating pressing elements, one of which is movable toward and from the other, fluid operated motor means for actuating the movable element, control means for the motor means, an operator-operated member for controlling the operation of the control means, said control means including valve means having a movable element operated by the operator-operated means different distances to vary the amount of motive fluid delivered to the motor means and hence vary the degree of pressure applied to the pressing element, and means for locking the operator-operated means in any one of a plurality of operated positions. 60
5. In a pressing machine, cooperating pressing elements, one of which is movable toward and from the other, motor means for actuating the movable element, control means for the motor means, an operator-operated member for controlling the operation of the control means, said control means including valve means having a casing with a pressure chamber therein connected to the motor and having an inlet and outlet and a normally closed spring pressed inlet valve in the inlet and a normally open, spring pressed valve in the outlet and pressure operated means for opposing the action of the springs of said spring pressed valve, said pressure operated means including resilient spring means and a member operable by the operator-operated means different distances to apply different tension to said resilient spring means and thus apply different pressures against the valve springs and hence vary the amount of motive fluid delivered to the motor means and the degree of pressure applied to the pressing elements, and means for preventing exhaust through the outlet of the valve casing and thereby locking the press closed. 65
6. In a pressing machine, cooperating pressing elements, one of which is movable toward and from the other; fluid pressure operated motor means for actuating the movable element to close the press successively under light and heavy pressure; means for controlling the flow of motive fluid to the motor including a casing having a pressure chamber; inlet and outlet valves connected to said chamber; springs normally holding the inlet valve closed and the outlet valve open; an operator-operated member and resilient means operated thereby for operating the valves against their springs with a force dependent upon the force applied by the operator to the operator-operated member; means connecting the chamber to the motor; and means operated by the motor when the press is closed under light pressure for preventing exhaust past the outlet valve of said chamber and thereby locking any desired amount of heavy pressure in said chamber, and hence locking the press closed under any desired amount of heavy pressure. 70
7. In a pressing machine, cooperating pressing elements, one of which is movable toward and from the other; fluid pressure operated motor means for actuating the movable element to close the press successively under light and heavy pressure; means for controlling the flow of motive fluid to the motor including a casing having a pressure chamber; inlet and outlet valves connected to said chamber; springs normally holding the inlet valve closed and the outlet valve open; an operator-operated member and resilient means operated thereby for operating the valves against their springs with a force dependent upon the force applied by the operator to the operator-operated member; means connecting the chamber to the motor; a safety valve connected to said connecting means for exhausting motive fluid above a predetermined degree of pressure; locking means for said safety valve connected to the exhaust valve of the pressure chamber and operated by the motive fluid escaping through said exhaust valve when the force applied to the operator-operated member is decreased; and an operator-operated normally open exhaust valve in the connection between the safety valve locking means and the exhaust valve of the pressure chamber for also controlling the operation of the safety valve locking means. 75
8. A garment or ironing press comprising, cooperative pressing elements one of which is mov- 80 85 90 95 100 105 110 115 120 125 130 135 140 145 150

- able with respect to the other, operating mechanism for the movable pressing element including motor means, means to supply working fluid to the motor means, pressure regulating means connected with the motor means and through which working fluid above a determined degree of pressure may exhaust from the motor means, and control means operable to actuate the working fluid supply means to supply working fluid to the motor means and render the pressure regulating means operative.
9. A garment or ironing press combining, cooperative pressing elements one of which is movable with respect to the other, operating mechanism for the movable pressing element including a motor means, means to supply working fluid to the motor means, pressure regulating means connected with the motor means through which working fluid above a determined degree of pressure may exhaust from the motor means and rendered inoperative upon actuation of the fluid supply means, a single control member, and connecting means operated thereby and operable in one position to operate the working fluid supply means to supply working fluid to the motor means and in another position to cut off the supply of working fluid to the motor means and render the pressure regulating means operative.
10. A garment or ironing press comprising, cooperative pressing elements one of which is movable with respect to the other, operating mechanism for the movable pressing element including motor means, means to supply working fluid to the motor means, pressure regulating means connected with the motor means and through which working fluid above a determined degree of pressure may exhaust from the motor means, and control means operable to actuate the working fluid supply means to supply working fluid to the motor means and render the pressure regulating means operative.
11. A garment or ironing press comprising, cooperative pressing elements one of which is movable with respect to the other to open and close the press, operating mechanism for the movable pressing element including motor means, means to supply working fluid to the motor means, including operator-operated control means connected with the working fluid supply means for supplying working fluid at high pressure to the motor means to effect closing of the press, and pressure regulating means controlled by said operator-operated control means and through which working fluid in excess of a determined degree of pressure may exhaust from the motor means when the operator-operated control means is operated to cut off the supply of working fluid to the motor means.
12. Operating mechanism for a garment or ironing press comprising, a motor, operator-operated control means for supplying working fluid to the motor, pressure regulating means connected with the motor and rendered inoperative when the operator-operated control means is actuated, the pressure regulating means having a check valve means through which working fluid above a determined degree of pressure may normally exhaust, the check valve means being operable when the operator-operated control means is operated to cut off the supply of working fluid to the motor.
13. A garment or ironing press comprising, cooperative pressing elements one of which is movable with respect to the other, operating mechanism for the movable pressing element including a motor, a single operator actuated control device, means operable when said device is in one position to supply working fluid to the motor, means operable when said device is in a second position to actuate the working fluid supply means to cut off the supply of working fluid to the motor and exhaust working fluid above a predetermined pressure from the motor, and means operable when said device is in a third position to exhaust all working fluid from the motor.
